Bernard S. Lee, Little Silver, N. J.

Application September 23, 1950, Serial No. 12,320

Term of patent 3½ years

(Cl. D33—14)

To all whom it may concern:

Be it known that I, Bernard S. Lee, a citizen of the United States, residing at Little Silver, in the county of Monmouth and State of New Jersey, have invented a new, original, and ornamental Design for Tables, of which the following is a specification, reference being had to the accompanying drawing, forming a part thereof.

The figure is a perspective view of a table, showing my design.

I claim:

The ornamental design for a table, as shown.
